UNITED STATES PATENT OFFICE.

JOHN B. BAXTER, OF WATERVLIET, NEW YORK, ASSIGNOR TO COVERT MANUFACTURING COMPANY, OF WATERVLIET, NEW YORK, A CORPORATION OF NEW YORK.

DESIGN FOR A HOOK.

• 50,177.

Specification for Design.

Patented Jan. 16, 1917.

Application filed October 29, 1915. Serial No. 58,713. Term of patent 14 years.

To all whom it may concern:

Be it known that I, JOHN B. BAXTER, a citizen of the United States, residing at Watervliet, in the county of Albany and State of New York, have invented a new, original, and ornamental Design for a Hook, of which the following is a specification, reference being had to the accompanying drawings, forming part thereof.

In the drawings: Figure 1 is a plan view of the front of the hook showing my new design; Fig. 2 is a corresponding rear view; and Fig. 3 is an edge view.

I claim:

The ornamental design for a hook, as shown.

JOHN B. BAXTER.
